US0D1057597S

(12) United States Design Patent (10) Patent No.: US D1,057,597 S
(45) Date of Patent: * Jan. 14, 2025

(54) PLANT CULTIVATION DEVICE

(71) Applicant: Yinru (Hangzhou) Technology Co., Ltd., Zhejiang (CN)

(72) Inventors: Le Kang, Zhejiang (CN); Zhaohui Li, Zhejiang (CN); Wenli Fan, Zhejiang (CN); Lina Jin, Shanghai (CN); Xuelong Liu, Shandong (CN)

(73) Assignee: Yinru (Hangzhou) Technology Co., Ltd., Zhejiang (CN)

() Term: 15 Years

(21) Appl. No.: 29/937,995

(22) Filed: Apr. 18, 2024

(30) Foreign Application Priority Data

Oct. 20, 2023 (CN) 202330679802.X

(51) LOC (15) Cl. 11-02

(52) U.S. Cl.

USPC D11/145; D11/144; D11/155

(58) Field of Classification Search

(57) CLAIM

The ornamental design for a plant cultivation device as shown and described.

DESCRIPTION

FIG. 1 is a front, right and top perspective view of a plant cultivation device, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the plant cultivation device that form no part of the claimed design.

1 Claim, 8 Drawing Sheets
